UNITED STATES PATENT OFFICE.

CHESTER G. VAN BUREN, OF CHICAGO, ILLINOIS.

LOOSE-LEAF BINDER.

1,380,755.

Specification of Letters Patent. Patented June 7, 1921.

Application filed June 26, 1918. Serial No. 241,912.

To all whom it may concern:

Be it known that I, CHESTER G. VAN BUREN, a citizen of the United States, and a resident of the city of Chicago, county of 5 Cook, and State of Illinois, have invented certain new and useful Improvements in Loose-Leaf Binders, of which the following is a specification.

My invention relates to improvements in 10 loose leaf binders, and has for its object the production of a device of this character which will be of durable and economical construction, and which will permit of ready and expeditious insertion and removal of 15 sheets.

Other objects will appear hereinafter.

The invention consists in the combinations and arrangements of parts hereinafter described and claimed.

20 The invention will be best understood by reference to the accompanying drawings forming part of this specification, and in which,

Figure 1, is a perspective view of a loose 25 leaf binder embodying the invention,

Fig. 2, an enlarged fragmental plan view of one of the covers of the binder,

Fig. 3, a view similar to Fig. 2, of the other cover of the binder,

30 Fig. 4, a fragmental detail section through the inner edge portion of the binder, the section being taken through one of the fastening means thereof,

Fig. 5, a section taken on line 5—5 of 35 Fig. 3,

Fig. 6, a plan view of the inner edge portion of a binder of slightly modified form,

Fig. 7, a section taken on line 7—7 of Fig. 6,

40 Fig. 8, a plan view of the inner edge portion of another form of the binder,

Fig. 9, a section taken on substantially line 9—9 of Fig. 8, and

Fig. 10, a detail section through the cover 45 of the binder upon which the fastening members are provided.

The preferred form of construction, as 50 illustrated in the drawings, comprises covers 11 and 12, each of which is formed adjacent its inner edge with a hinge 13 to permit of ready swinging of the covers. The sheets or leaves 14 to be bound in the binder are arranged between the covers 11 and 12, as clearly seen in the several views.

55 Provided adjacent the inner edge of the cover 11 are two spaced upwardly extend-

ing flexible fastening members 15, formed preferably of metal, the inner ends thereof being united, if desired, so that but a single piece of material will be employed, the fastening members 15 being constituted by the ends of the piece. Provided in the cover 12 adjacent the inner edge thereof are two spaced openings 16, the same being separated at such a distance as to adapt the same 60 to receive the ends of the fastening members 15, as will be readily understood. The covers are locked together by bending back or clenching the upper or outer ends of the members 15 after the latter have been passed 65 through the openings 16. Said ends of the members 15 are held in clenched condition by means of a blade 17 pivotally secured at 18 to the cover 12. The arrangement is such that the blade 17, after clenching of the ends of members 15, is adapted 70 to be swung to position thereover, as seen in Figs. 1 and 4. In order to securely hold the blade 17 in operative relation with the fastening members 15, an upwardly and forwardly projecting flange 19 is provided, 75 which is rigidly secured to the rearward edge of cover 12, said blade, when in operative relation with the fastening members, assuming a position under the flange 19, as 80 clearly seen in Figs. 1 and 4. The frictional engagement of said blade with the flange 19 will be sufficient to securely hold the same 85 in position thereunder.

Where the openings 16 are spaced a considerable distance apart, as seen in Fig. 6, two blades 17 will be employed, one co-operative with each of the fastening members 15, said blades being adapted to assume positions under the lengthened flange 19 in precisely the same manner as described with reference to the construction disclosed in Fig. 1.

Also, if desired, fastening members may be in the form of covered wires 15', the wires being cylindrical in form, and thus less apt to cut the sheets or leaves inserted into the binder. By employing covered wires, that is, wire with an inclosing casing surrounding the same, in the event of the wire itself breaking, through successive bending thereof, the casing will still be sufficient to hold the fastening device together and operative, thus lengthening the life of the binder, as will be readily understood.

In the fastening of the sheets in the binder, the fastening devices are passed

through openings provided in the inner edge portions of the sheets, as will be readily understood. The sheets may be readily and easily perforated for this purpose prior to 5 insertion of the same into the binder by simply inserting the inner edge of each sheet under the flange 19 and then puncturing the sheet at the opening 16 by means of a pencil or other suitable perforating tool.

10 To guide the operator in thus perforating the sheet, the forward edge of the flange 19 is formed with recesses or notches 20 which serve to indicate the positions of the openings in the cover, as will be readily understood. In thus perforating the sheet, the same is placed centrally upon the cover 12, and with the inner edge thereof resting under the flange 19, the cover 11 having been detached from the cover 12 and the 15 blade 17 rocked to the position seen in Fig. 2.

20

While I have illustrated and described the preferred forms of construction for carrying my invention into effect, these are 25 capable of variation and modification without departing from the spirit of the invention. I, therefore, do not wish to be limited to the precise details of construction set forth, but desire to avail myself of such 30 variations and modifications as come within the scope of the appended claims.

Having described my invention, what I claim as new and desire to secure by Letters Patent is:—

- 35 1. A binder or file for sheets of paper or the like, comprising a pair of covers; spaced flexible fastening means arising from one of said covers adjacent the inner edge thereof, and adapted to pass through openings provided in the other cover and be clenched over the latter; a flat blade on said last mentioned cover, pivotally connected therewith, adapted to be adjusted to engage over the clenched ends of said fastening means to hold the same in clenched condition; and a flange on said last mentioned cover under which said blade is adapted to engage when in operative relation with said fastening means, said flange extending parallel with said blade when the latter is in engagement therewith and engaging with said blade throughout substantially its entire length, substantially as described.
- 40 2. A binder or file for sheets of paper or the like, comprising a pair of covers; spaced flexible fastening means arising from one of said covers adjacent the inner edge thereof, and adapted to pass through openings pro-
- 45 50

vided in the other cover and be clenched over the latter; a flat blade on said last mentioned cover, pivotally connected therewith, adapted to be adjusted to engage over the clenched ends of said fastening means to hold the same in clenched condition; and a flange on said last mentioned cover projecting outwardly and forwardly from the inner edge of said last mentioned cover, under which said blade is adapted to engage when in operative relation with said fastening means, substantially as described.

3. A binder or file for sheets of paper or the like, comprising a pair of covers; spaced flexible fastening means arising from one of said covers adjacent the inner edge thereof, and adapted to pass through openings provided in the other cover and be clenched over the latter; a flat blade on said last mentioned cover, pivotally connected therewith, adapted to be adjusted to engage over the clenched ends of said fastening means to hold the same in clenched condition; a flange on said last mentioned cover projecting outwardly and forwardly from the inner edge of said last mentioned cover, under which said blade is adapted to engage when in operative relation with said fastening means; and means on said flange adapted to indicate the position of said openings in said cover, substantially as described.

4. A binder or file for sheets of paper or the like, comprising a pair of covers; spaced flexible fastening means arising from one of said covers adjacent the inner edge thereof, and adapted to pass through openings provided in the other cover and be clenched over the latter; a flat blade on said last mentioned cover, pivotally connected therewith, adapted to be adjusted to engage over the clenched ends of said fastening means to hold the same in clenched condition; a flange on said last mentioned cover projecting outwardly and forwardly from the inner edge of said last mentioned cover, under which said blade is adapted to engage when in operative relation with said fastening means; and recesses in the forward edge of said flange adapted to indicate the position of said openings in said cover, substantially as described.

In testimony whereof I have signed my name to this specification in the presence of two subscribing witnesses.

CHESTER G. VAN BUREN.
